UNITED STATES PATENT OFFICE.

JOSE B. COLÓN, OF GREENEVILLE, TENNESSEE.

BOTTLE.

1,075,900.

Specification of Letters Patent. Patented Oct. 14, 1913.

Application filed September 20, 1912. Serial No. 721,503.

To all whom it may concern:

Be it known that I, JOSE B. COLÓN, a citizen of the United States, residing at Greeneville, in the county of Greene and State of Tennessee, have invented a new and useful Bottle, of which the following is a specification.

This invention relates to bottles and more particularly to bottles of that type 10 designed for holding medicine.

Heretofore prescription bottles have been found objectionable because liquid flowing or dripping from the mouths of the bottles often drops onto the label affixed to the 15 bottle and obliterates the prescription number so that it is thus impossible to determine the number of the prescription when it is desired to renew the same.

One of the objects of the present invention is to provide the bottle with means whereby any liquid which may flow or drip 20 downwardly from the mouth thereof will be deflected laterally so as not to pass onto the label affixed to the bottle.

With the foregoing and other objects in view which will appear as the description proceeds, the invention resides in the combination and arrangement of parts and in the details of construction hereinafter 25 described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a front 40 elevation of a bottle having the present improvements combined therewith. Fig. 2 is a rear elevation thereof. Fig. 3 is a section on line A—B Fig. 1. Fig. 4 is a section through a portion of a slightly modified 45 form of bottle.

Referring to the figures by characters of

reference 1 designates a prescription bottle of any desired contour and the shoulder portion 2 of the bottle has a drain channel or groove 3 pressed into the front portion 50 thereof, this channel being preferably extended about half around the bottle and being preferably formed with its middle portion uppermost and its discharge ends lowermost so that any liquid which may be deposited in the channel or groove will drain 55 to one end or the other of the channel. The label, which has been indicated at 4, is to be affixed to the bottle directly below the middle portion of the channel 3. Obviously, 60 therefore, any liquid which may flow downwardly along the front portion of the bottle neck or which may drip downwardly from the front portion of the mouth of the bottle, will be received by the channel 3 65 and conveyed laterally so as not to flow downwardly onto the label.

It will be seen that a channel such as herein described can be readily formed within the bottle without adding to the 70 cost thereof and without weakening the bottle or marring its appearance.

Instead of forming a depression in the front of the bottle, an outstanding rib such as shown at 5 in Fig. 4 can be used. 75

What is claimed is:—

A bottle having a label receiving surface and means for protecting said surface from drippings from the bottle neck, said means including a gutter formed in the bottle above 80 the label receiving space, the said gutter draining onto the outer surface of the bottle at points removed from the label receiving space.

In testimony that I claim the foregoing 85 as my own, I have hereto affixed my signature in the presence of two witnesses.

JOSE B. COLÓN.
